UNITED STATES PATENT OFFICE.

MARTIN ZEH, OF BERLIN, GERMANY, ASSIGNOR TO THE FIRM DR. ERICH F. HUTH GES.
M. B. H., OF BERLIN, GERMANY.

MOUNTING FOR THERMIONIC TUBES.

Application filed January 19, 1926, Serial No. 82,205, and in Germany January 27, 1925.

The present invention relates to means for mounting thermionic tubes such as are used in radio receiving sets. By the present invention it is proposed to so construct a mounting 5 for such thermionic tubes as will permit the same mounting to be used for any of the various sized tubes now being used in the several different makes of broadcast receiving sets.

Furthermore, it is the object of this invention to provide a construction of mounting that will be economical to manufacture and which will at the same time improve the operating characteristics of the mounting.

My invention may be best understood from 15 the accompanying drawings, wherein

Figure 1 is a top plan view of one embodiment of my invention;

Fig. 2 is a side elevation, and

Figs. 3 and 4 are detail views.

20 By the present invention the terminal pins of the thermionic tubes are clamped underneath the base plate of the mounting by laterally movable pressure springs which firmly hold each contact pin.

25 The mounting is provided with a plurality of holes of greater length than diameter and the pressure springs are so mounted and constructed that pressure contact is obtained on the terminal pin of the thermionic tube re-

30 gardless of the position of the contact pin in the elongated hole. By such construction, it is also possible to have a mounting using a single pressure contact spring.

Referring to the drawings, a base plate 1, 35 which is preferably constructed of insulating material, is provided with a plurality of elliptical holes arranged at right angles to each other. In the design of the mounting, the narrow axes of these holes are made large 40 enough to receive the largest terminal pin of thermionic tubes now in use and the longer axes are so proportioned as to be larger than the diameter of the terminal pins of the thermionic tube and long enough to accommodate 45 the pins that are farthest apart on the thermionic tubes now in use.

A plurality of angular brackets 3 are secured to the lower side of the base 1 by any proper means such as the screws 3' shown in 50 Fig. 1.

The short leg of the bracket 5 is provided with a reduced extension 7 which is adapted to be bent upwardly and when the brackets 3 are assembled on the base 1, the extension 7 55 engages in the hole 8 in the base 1 as shown

in Fig. 1. Each bracket is similarly constructed and mounted. It will be noted that the extension 7 is rectangular and that the hole 8 is also rectangular. In this way, the bracket 7 is securely held from rotary movement.

Each of the brackets 3 has secured thereto a pressure spring 4. The spring is so mounted and formed as to be normally biased to a position wherein it extends partially across 65 an opening 2. As shown in Fig. 1, the spring extends more than half way across the width of this opening. Accordingly, the width of the contact spring is normally designed to extend over the entire length of the opening 70 2.

As the thermionic tube is inserted in the mounting described above, the terminal pins will enter the opening 2 and move the springs 4 laterally. In order to guide this 75 lateral movement of the springs, the springs are designed with a flat, contracted portion 9 which extends through and is guided in an opening 10 in the respective brackets 3. Since it is desirable to limit the outward or 80 lateral movement of the springs 4, the free ends thereof are bent downwardly as indicated at 11 in Fig. 3.

In the embodiment shown in the present drawings, the springs 4 are riveted to the 85 brackets 3. In order that circuit connections may be made to the brackets 3 and through the brackets 3 and springs 4 to the terminal pins of the thermionic tube, an extension 12 is provided on the long leg of the bracket 90 3 to which connections may be made by soldering.

Modifications may be made in the arrangement, location and construction of parts within the spirit and scope of my invention 95 and such modifications are intended to be covered by the appended claims.

I claim:

1. A mounting for thermionic tubes comprising a base member provided with elliptically shaped apertures to receive thermionic tubes of different type of pin terminal arrangement, bracket members adjacent said apertures depending from the under surface of said base member, each of said bracket 100 members having a short portion secured to the under surface of said base member and a longer portion extending substantially at right angles to the short portion, and a resilient member carried by said longer portion 105 110

and extending over the corresponding one of said apertures to exert contact pressure on said pin terminals in a direction of the small axis of said elliptic apertures.

5 2. A mounting for thermionic tubes comprising a base member provided with elliptically shaped apertures to receive thermionic tubes of different type of pin terminal arrangement, bracket members adjacent said apertures depending from the under surface of said base member, each of said bracket members having a short portion secured to the under surface of said base member and a longer portion extending substantially at right angles to the short portion, and a resilient member carried by said longer portion and extending over the corresponding one of said apertures to exert contact pressure on said pin terminals in a direction of the small axis of said elliptic apertures, said resilient member having a guide passing through the bracket member in a position intermediate said short portion and said longer portion.

10 25 3. A mounting for thermionic tubes comprising a base member provided with elliptically shaped apertures to receive thermionic tubes of different type of pin terminal arrangement, contact supports carried by said base member, resilient elements extending over said apertures to extend contact pressure on said pin terminals in a direction of the small axis of the elliptic apertures, each of said contact supports comprising an 15 20 25 30 35 angularly disposed strip member with one

end of said strip member secured beneath said base member and the other end of said strip member carrying one of said resilient elements, said strip members being furthermore slotted intermediate their ends and a tongue extending from one end of each of said resilient elements through said slotted strip member for limiting the lateral movement of said resilient contact with respect to said strip member.

4. A mounting for thermionic tubes comprising a base provided with two pairs of elliptically shaped apertures, each pair being arranged diametrically along two lines perpendicular with respect to each other with the longer axis of the ellipse pointing in the direction of said lines, said apertures being large enough to receive thermionic tubes of different type of pin terminal arrangement, contact supports carried by said base, each contact support including a metallic strip bent substantially at right angles and depending from said base, a resilient contact member carried by said contact supports and extending each over one of said apertures to exert contact pressure on said pin terminals in a direction of the small axis of the elliptic aperture, and means for guiding said contact member in a lateral direction with respect to said contact support.

In testimony whereof I affix my signature.

MARTIN ZEH.
